UNITED STATES PATENT OFFICE.

JOHN C. KANE AND FRANCIS E. HUGG, OF DETROIT, MICHIGAN.

HEATER FOR AUTOMOBILES.

1,104,120.

Specification of Letters Patent. Patented July 21, 1914.

Application filed April 6, 1914. Serial No. 829,976.

To all whom it may concern:

Be it known that we, J. C. KANE and FRANCIS E. HUGG, citizens of the United States, residing at Detroit, in the county of Wayne and State of Michigan, have invented certain new and useful Improvements in Heaters for Automobiles, of which the following is a specification.

This invention relates to improvements in gas heaters, and has particular reference to a gas heater so constructed that the same is of the proper shape and size to be installed within or upon an automobile, in an out of the way position.

15 An important object of the invention is to provide a gas heater of the above mentioned character, which is of simple construction, inexpensive to manufacture, compact, and adapted to be arranged below the seat of an automobile, while not necessarily restricted to such location.

Other objects and advantages of the invention will be apparent during the course of the following description.

25 In the accompanying drawings forming a part of this specification and in which like numerals are employed to designate like parts throughout the same, Figure 1 is a front elevation of a gas heater embodying the invention, Fig. 2 is a transverse sectional view taken on line 2—2 of Fig. 1, Fig. 3 is a front elevation of the same, with the front plate removed, and Fig. 4 is a horizontal sectional view taken on line 4—4 of Fig. 3.

35 In the drawings, wherein for the purpose of illustration is shown a preferred embodiment of the invention, the numeral 5 designates the body portion of the heating shell or casing, the same being of sheet metal, and 40 including a flat back 6, sides 7, a horizontal floor or bottom 8, and a forwardly extending inclined top 9, as shown. The forward side of the body portion 5 is formed open, and is normally closed by a front plate 10, and is 45 formed of sheet metal, adapted to engage with and be secured to an outwardly extending flange 11 formed upon the body portion 5, as shown. It is thus seen that the construction of the heating shell or casing is 50 compact, the same being adapted to be verti-

cally arranged when in use. The upper portion of the inner surface of the back 6 and top 9 is lined with a sheet of asbestos 11', as shown. Arranged within the main heating shell or casing is an inner partition 12, 55 formed of sheet metal and affording a vertical chamber 13. The vertical edges of this partition 12 are provided with flanges 14, secured to the front plate 10, by means of bolts or rivets 15, as shown. The lower end 60 of the partition 12 is spaced a substantial distance from the floor or bottom 8 and the upper end of the same is spaced a substantial distance from the inclined top 9, as shown. 65

Mounted within the partition 12 or chamber 13 are a plurality, two being considered an advantageous number, of vertical tubes 16, arranged in spaced relation and rigidly connected with the side of the partition 12 70 by means of bolts or rivets 17, as shown. The upper end of the partition 12 is bent forwardly to form an inclined top 18, passing above the upper end of the tubes 16 (the upper and lower ends of these tubes being 75 open), and projecting outwardly beyond the front plate 10, in the form of a downwardly inclined deflector 19, as shown. The front plate 10 is provided with horizontal openings 20 and 21, arranged above and below 80 the deflector plate 19, as more clearly shown in Fig. 2.

Extending into the lower portion or the bottom of the main heating shell or casing is a preferably horizontally arranged gas 85 supply pipe 22, adapted to have connection with the acetylene gas tank carried by an automobile and which is ordinarily employed to supply gas to the headlights of the machine. This pipe is preferably provided with a cut-off valve 23, arranged within the main heating shell or casing, with its stem 24 extending outwardly through an opening in the front plate 10, the same being preferably formed square in cross-section 90 for engagement with a wrench or suitable tool, to turn the same. 95

Connected with this gas supply pipe 22 by means of T-couplings 25 are gas burners 26, which I have found may be of the same 100

type as ordinarily used in the headlights of an automobile, the same being adapted to burn acetylene gas. The upper forked ends of these acetylene gas burners 26 extend into 5 the lower ends of the tubes 16 for a substantial distance. Adjacent the upper end of these burners, the tubes and front plate 10 are provided with openings 27, to afford access to the burners whereby the same may 10 be lighted, said openings being normally closed by swinging doors 28, pivoted at 29. Below these doors 28 the front plate 10 is apertured or provided with air supply openings 30 through which air passes, to travel 15 through the air passage 31, as indicated by the arrows in Fig. 2.

As clearly shown in Fig. 2, the numeral 32 designates a portion of the seat of an automobile, while the numeral 33 designates a 20 portion of the floor of the same. The heater is adapted to be arranged below the seat 32, and is connected at its upper end with the seat by means of screws 34 or the like, passing through apertured flanges 11 formed 25 upon the body portion 6 and the apertured edge of the front plate 10. At its lower end the main heating shell 5 is secured to the floor 33 by means of screws 36 or the like passing through apertured flanges 11 30 and the apertured lower end of the front plate 10, as shown.

In the operation of the heater, assuming that the same is arranged below the seat of an automobile, where it is particularly 35 adapted to be disposed while not necessarily restricted to such location, the burners 26 being lighted, the products of combustion or heated gases pass upwardly through the tubes 16. These products of combustion are 40 deflected forwardly by the top 18, and pass through opening 21, and are again deflected downwardly by the deflector plate 19. By the time the products of combustion have 45 passed from in proximity to the deflector plate 19 they are sufficiently cooled whereby they will not over heat the feet or legs of the occupant of the automobile. The heat within the tubes 16 heats the air within the passage 31, causing the same to circulate upwardly therein, this air entering through 50 apertures 30, passing upwardly through passage 31, deflected forwardly between tops 9 and 18, and discharging forwardly and upwardly through opening 20. This air 55 does not attain a heat sufficiently high to cause inconvenience to the occupant of the car and is deflected upwardly to heat the upper portion of the car.

It is to be understood that the form of 60 the invention herewith shown and described, is to be taken as a preferred example of the same, and that various changes in the shape, size, and arrangement of parts may be resorted to without departing from the spirit

of the invention or the scope of the sub- 65 joined claims.

Having described the invention, what is claimed is:

1. In a gas heater for automobiles or the like, a main upstanding heating shell having one side thereof formed open, a removable plate covering the open side of the heating shell and provided near its lower end with an air inlet opening and near its upper end with a gas discharge opening, a 70 partition secured to the inner side of the removable plate and having the upper end thereof bent to form an inclined top portion arranged adjacent the gas discharge opening, and a burner arranged within the 75 lower end of the main heating shell and adapted to discharge products of combustion into the chamber formed by the partition and plate.

2. In a gas heater for automobiles or the like, a main upstanding heating shell having one side thereof formed open, a removable plate to cover the open side of the heating shell and provided near its lower end with air inlet openings and near its upper end with a discharge opening, a partition secured to the inner side of the removable plate and extending longitudinally within the heating shell and having its upper end provided with a laterally extending 90 top portion passing through the discharge opening to divide the same into hot air and gas discharge openings, a plurality of open ended tubes arranged between the plate and the partition and secured thereto, a gas supply pipe arranged within the lower portion of the heating shell, and burners secured to the gas supply pipe and extending into 95 proximity to the lower ends of the tubes.

3. In a gas burner for automobiles or the like, a main upstanding heating shell having one side thereof formed open and provided with outwardly extending flanges to serve for securing the heating shell to a support, a removable plate covering the open side of the heating shell and provided near its lower end with air inlet openings and near its upper end with an outlet opening, upstanding tubes arranged within the heating shell and secured to the removable 105 plate with their upper ends disposed in proximity to the outlet opening, and burners arranged within the lower portion of the heating shell with their upper ends extending into the lower ends of the tubes, substantially as described.

4. In a gas heater for automobiles or the like, a main heating shell having one side thereof formed open, a removable plate covering the open side of the heating shell and provided near its lower end with an air inlet opening and near its upper end with a gas discharge opening, a partition secured to 110

the inner side of the removable plate to form therewith a gas passage leading into the gas discharge opening, and a burner arranged within the lower end of the main heating shell and adapted to discharge products of combustion into said gas passage, substantially as described.

In testimony whereof we affix our signatures in presence of two witnesses.
